[57] CLAIM

The ornamental design for “faucet handle”, as shown and described.

DESCRIPTION

FIG. 1 is a perspective view of faucet handle showing my new design;

FIG. 2 is a front view thereof;

FIG. 3 is a rear view thereof;

FIG. 4 is a left side view thereof, the right side is identical;

FIG. 5 is top view thereof; and,

FIG. 6 is a bottom view thereof.

The broken line showing is for illustrative purposes only and forms no part of the claimed design.
